UNITED STATES PATENT OFFICE.

ALONZO WOLFANGER, OF TRENTON, NEW JERSEY.

SUPPORT FOR RIVETING-TOOLS.

1,364,015.

Specification of Letters Patent. Patented Dec. 28, 1920.

Application filed May 10, 1920. Serial No. 380,320.

To all whom it may concern:

Be it known that I, ALONZO WOLFANGER, a citizen of the United States, residing at Trenton, in the county of Mercer and State 5 of New Jersey, have invented new and useful Improvements in Supports for Riveting-Tools, of which the following is a specification.

This invention relates to supports for riveting tools and it has more particular reference to what may be termed adjustable pedestals or stands, the main object being to provide a stand for a riveting hammer by the use of which said hammer can be employed for riveting in awkward positions and where it has been necessary heretofore to employ at least two men, one to support the hammer and another to manipulate and operate the same.

Another object of my invention is to provide a support for riveting hammers by which the weight of the tool is counterbalanced in such a manner that it can be readily handled by one operator whereby a great 25 saving in labor and time is effected.

Still further the invention has for an object to provide a support whereby the riveting hammer can be held in any desired position and manipulated under a flat, inclined 30 or curved surface with perfect ease.

With the foregoing and other objects in view as will later on be more apparent this invention consists essentially in certain novel features of construction, combinations and 35 arrangements of parts as hereinafter fully described and more specifically defined by the appended claims.

In the further disclosure of the invention reference is to be had to the accompanying 40 sheet of drawings constituting a part of this specification in which similar characters of reference designate the same or corresponding parts in all the views.

Figure 1 is an elevation of my improved 45 support for riveting tools, parts being broken away for the sake of clearness.

Fig. 2 is an enlarged fragmentary detail 50 of a portion of the pedestal and counterbalance, with parts in section to better disclose the underlying structure; and

Fig. 3 is a detail plan of a supporting member hereinafter more specifically referred to.

Referring to the drawings, the numeral 55 10 designates flattened arch members provided with laterally projecting feet 11 and

disposed in cruciform manner to intersect at their flattened parts 12. These arched members 10 at their point of intersection are perforated and screw threaded at 13 to receive the correspondingly threaded end of a vertical tubular section or standard 14, in which is slidably fitted a rod or bar 15, the lower end whereof is reduced at 16 to seat in a trunnion ring or bearing 17 pivotally mounted in the forked end 18 of a lever 19. This lever 19 is provided with a pivot pin 20 or opposed laterally projecting pintles adapted for seating in opposed inclined slots or notched out parts 21 formed for their reception in a pair of spaced depending links 22 appropriately suspended by a pivot pin or bolt 23, transversely projecting from the vertically twisted or turned part 24 of a horizontally disposed supporting element or 75 flat iron 25 preferably clamped between the lower flanged end 26 of the aforesaid tubular standard 14 and the intersecting flattened portions 12 of the arched members 10, forked projections or extensions 27—Fig. 3—thereof being secured by bolts or rivets 28 to the flattened out parts of the said arched members whereby a rigid structure is secured when the several parts are assembled as shown.

Adjustable longitudinally of the lever 19 by means of cotter pins or bolts 29 is a saddle box or receptacle 30 in which may be deposited weights 31 of different weight, for the purpose hereafter explained.

Integral with or firmly secured on the upper end of the slideable rod or bar 15 is an inverted stirrup bearing 32 transversely of which is rotatably mounted a grooved roller 33 that constitutes a support for a 95 tubular or round iron bar 34 on one end whereof is swivelingly mounted an upstanding antifriction roller or caster 35, the other end of said bar being provided with an eyed portion 36 from which depends a stirrup 37, having opposed slots 38 for the reception of pintles 39 on a locking ring 40 adapted for clamping engagement on the barrel of the riveting hammer 41, it being readily understood that the said hammer 100 also projects upwardly through the eyed portion 36 of the bar and that its head or handle portion seats on the lower part 42 of the stirrup 37. It is also to be particularly noted that when the hammer 41 is 110 mounted in the stirrup 37 as shown, that the barrel and die 43 project thereabove only

sufficient to insure the bar 34 remaining in a substantially horizontal plane when the device is in use under a flat surface as indicated by the dot-and-dash line 44; or, as 5 will be readily understood by those skilled in the art of riveting, the die 43 of the hammer 41 is always in direct alinement with the rolling surface or edge of the caster 35 and both are substantially parallel to the 10 axis of the bar 34 when the device is in use. Furthermore it is to be particularly noted that a sufficient weight or weights 31 are deposited in the saddle box 30 to counterbalance the weight of the hammer 41 at 15 whatever radial distance from the axis of the standard 14 it is desired to be used so that the operator is relieved from all strain in supporting said hammer and is free to manipulate the same promptly and expeditiously 20 over the desired seam or surface; while the prompt dismantling of the entire device can be readily effected and thereby rendering said device easily portable and compact for shipment.

25 From the foregoing description of the embodiment of my invention shown by the accompanying drawings it becomes clear that I have provided an efficient means for supporting a riveting hammer and I wish 30 it clearly understood that I do not limit myself to the precise details of shape or the particular arrangement and combination of parts disclosed, as various slight changes can be readily evolved without departing 35 from the spirit and scope thereof as more particularly defined by the appended claims.

Having described my invention, what I claim as new and desire to secure by Letters 40 Patent, is:—

1. A support for riveting hammers comprising in combination, a vertical tubular section having laterally flared basal members, a vertically movable and rotatably mounted element in said tubular section, a lever fulcrumed on the basal members and having supporting connection with the lower end of the vertically movable element, a counterbalance on said lever, a bar longitudinally movable on the upper end of the vertically movable element, an upstanding caster at one end of said bar, and depending hammer supporting means at the other end thereof.
- 55 2. A support for riveting hammers comprising in combination, a vertical tubular pedestal having laterally flared leg portions, a shaft vertically movable and rotatable in said tubular pedestal, a lever adjustably fulcrumed on a laterally projecting arm on said pedestal and having supporting connection with the lower end of the aforesaid shaft, a variable counterbalance supported on the free end of the lever, a longitudinally mov-

able bar supported at the upper end of the 65 shaft, an upstanding caster at one end of said trolley bar, and depending hammer supporting means at the other end thereof.

3. A support for riveting hammers comprising in combination, a vertical tubular 70 pedestal having laterally flared leg portions, a shaft vertically slidable and rotatable in said tubular pedestal, a laterally projecting arm on said pedestal, depending links pivotally mounted thereon and having 75 downwardly inclined stepped notches, a lever fulcrumed between said links and having supporting connection with the lower end of the aforesaid shaft, a variable counterbalance adjustably supported on the free 80 end of the fulcrumed lever, a longitudinally movable bar supported at the upper end of the vertical shaft, an upstanding caster at one end of said bar, and depending hammer supporting means at the other end thereof. 85

4. A support for riveting hammers comprising in combination, a vertical tubular pedestal having laterally flared leg portions, a shaft vertically slidable and rotatable in said tubular pedestal, a laterally 90 projecting arm on said pedestal, depending links pivotally mounted thereon and having downwardly inclined stepped notches, a lever fulcrumed between said links and having supporting connection with the lower 95 end of the aforesaid shaft, a variable counterbalance adjustably supported on the free end of the fulcrumed lever, a longitudinally movable bar supported at the upper end of the vertical shaft, an upstanding caster at 100 one end of said bar, a swingingly mounted stirrup at the other end thereof, and means for clamping a riveting hammer in said stirrup.

5. A demountable support for riveting 105 hammers comprising in combination, a vertical tubular member, arched supporting members removably attached at the lower end of said tubular member, a shaft vertically slidable and rotatable in the tubular 110 member, a laterally projecting arm having removable connection with the tubular and arched supporting members, spaced links pivotally suspended from the aforesaid arm and having downwardly inclined alining 115 notches therein, a lever fulcrumed between said links and having supporting connection with the lower end of the vertical shaft, a variable counterbalance adjustably supported on the free end of the fulcrumed 120 lever, a longitudinally movable bar mounted on the upper end of the vertical shaft, an upstanding caster at one end of the bar, a swingingly mounted stirrup at the other end thereof, and means for clamping a riveting 125 hammer in said stirrup.

In testimony whereof I affix my signature.
ALONZO WOLFANGER.
